DRAWING TABLE

Miller B. Cook, Beloit, Wis.

Application July 17, 1937, Serial No. 154,160

6 Claims. (Cl. 45—131)

The present invention relates to drawing tables suitable for nurseries, drawing schools, art schools, studios, and the like, and has for its object providing one or two adjustable drawing boards thereon having means for supplying paper therefor from a roll or rolls positioned within the table.

An object of the present invention is to provide a simple, easily manufactured, light and efficient table for the purpose.

A further object of the present invention is to provide a table which may be equipped with one or two drawing boards, and wherein when two boards are provided they may be used simultaneously or alternately without interfering one with the other.

A further object of the present invention is to provide a drawing table having a roll of paper for each individual board and means whereby the paper is not cut free from the roll until after it has been used and a fresh surface moved on the board; and whereby the paper between the board and roll will not interfere with the movement of the board.

Another object of my invention is to provide simple means for adjusting and locking the board at any desired angle from horizontal to vertical.

A further object of the present invention is to provide a table for nursery use whereby suitable papers, having sketches, may be placed under the semi-transparent paper from the roll for tracing purposes; or whereby, the outline of animal forms and the like may be placed on the rolls for juvenile tracing, copying, or coloring purposes.

To these and other useful ends my invention consists of parts, combinations thereof or their equivalents and mode of operation as hereinafter described, and claimed and shown in the accompanying drawings in which:

Fig. 1 is a side elevation of my improved drawing table.

Fig. 2 is a front elevation of the device viewed from the left of Figure 1.

Fig. 3 is a top view of the drawing board after being detached from the table but retaining the paper from the roll and having thereunder a typical sketch from which to trace or color.

Fig. 4 is a front view of the board as shown in Figure 3.

Fig. 5 is a detail of one of the holding and guiding devices for the upper end of the board taken on line 5—5 of Figure 1.

As thus illustrated, my invention consists of two end members 10—10 each formed preferably

from a U shaped channel as illustrated in Figure 5. I provide a sheet metal panel 11 which is preferably shaped as shown and spot welded or otherwise secured to members 10, thus to improve the appearance and strengthen the table 15 and form unitary end members. These members are detachably secured together by means of a sheet metal plate 12, and suitable cross braces 13.

I provide holding brackets 14—14 which are secured to members 11 as illustrated by dotted 10 lines in Figure 1 on which the rolls of paper 15—15 may be supported and easily removed and replaced.

It will be understood that the form of table shown in Figure 1 is optional. I may elect to use 15 but one side of this table, leaving the other side vertical or as shown and close it with a panel which extends from member 12 to the bottom edges of members 11. I may also elect to place drawers or shelves in the rear, sides, or front 20 of the table.

I provide novel means for supporting and adjusting the drawing boards 20—20. The lower ends are supported by means of links 21—21; these links are preferably pivoted at their bottom ends 25 to the end members in any suitable manner by means of bolts as at 22—22 and at their upper ends to the table as at 23—23.

I provide roller supports and holding means for the upper end of the board as follows: Brackets 30 30—30 are provided which are secured to the board 20 as clearly indicated in Figure 5 each having slidably mounted pins 31—31. These pins are reduced in diameter to thereby form offsets as at 32, the reduced end 33 being adapted to rotatably carry the rollers 34—34. Rollers 34 are provided with flanges 35. Pin 31 is provided with a spring 36 and a cotter pin 37 whereby the roller 34 is yieldably held in the position shown in Figure 5.

I provide a suitable number of orifices 33 40 whereby when the roller is held in the channel as illustrated, the protruding end of member 33 will project through these orifices; thus it will be seen that the upper end of the board may be 45 securely held in any desired position.

To release the board all that is necessary is to press inward against flanges 35 with sufficient pressure to overcome the pressure of springs 36, thus to cause members 33 to disengage orifices 33 50 and when this is done the rollers will then be free to move upward and downward in the channel and the board may thus be moved and locked to any desired position.

The lowest orifices are positioned whereby the 55

board may be placed and held in a horizontal position as illustrated on the left in Figure 1. The highest preferable position of the board is illustrated on the right of Figure 1 and an intermediate position is illustrated by dotted lines on the left of Figure 1.

I provide preferably suitable paper holding strips 40—40. Bolts 41 and thumb nuts 42 are also provided. The bolts pass through orifices in strips 40; thus the paper may be positioned and held under these strips. By referring to Figure 1 it will be noted that the paper is threaded under the inner strip and extends over the board and is threaded under the outer strip, the loose end protruding as at 43.

After the paper on the board has been used, the thumb nuts are loosened and the paper pulled so a fresh surface is supplied to the board and made fast as already explained. The used portion of the paper is torn off as at 43.

Thus it will be seen that the board may be easily secured in any desired position, and that the used paper may be conveniently replaced from a continuous supply. It will also be noted that when the board is moved from one position to the other the paper roll will accommodate this movement as illustrated by dotted lines in Figure 1.

It will be understood that the connections between the two end members are preferably detachable, thus the end members may be laid flat and packed with the boards and other parts in a neat shipping container.

Clearly, applicant's invention is particularly suited for juvenile use as well as for studios, class rooms, etc. In Figure 3, I illustrate by dotted lines a sheet of paper, having thereon, the outline of a rabbit. Such sheets may be supplied to the trade and they may be used as many times as desired. I have also contemplated printing various lines and figures on the roll of paper.

It will be understood that various minor changes may be made in the details shown and described without departing from the spirit and scope of the invention as recited in the appended claims.

Having thus shown and described my invention I claim:

1. A device of the class described, comprising a drawing board and supporting means therefor having spaced inwardly turned channels, supports secured to the upper ends of said board and adapted to be loosely engaged by said channels and having locking means, links pivotally secured at their upper ends to said board a distance from said supports and being pivotally secured at their lower ends to said supporting means whereby said board may be moved and locked into selective angles, said board having paper fastening means at its front and rear edges, a roll of paper rotatably supported on said supporting means and being positioned whereby the end of the paper from said roll may be positioned and clamped on said board, and whereby said board may be moved to any desired angle without disengaging the paper from the roll.

2. A device of the class described, comprising end members and means therebetween forming a stand, two drawing boards adjustably supported on opposite sides of said stand, said supporting means comprising slides on said end members, guides on the upper end of said board being adapted to be engaged by said slides, links pivotally secured at their upper ends to said boards a distance from said guides and pivotally se-

cured at their other ends to said end members, whereby said boards may be moved to selective angles, means adapted to lock said boards in their selective positions, two rolls of paper rotatably supported between said end members and positioned, whereby the paper may be threaded over and locked to said boards and whereby said boards are free to be moved to various positions without detaching the paper from said rolls.

3. A device of the class described, comprising spaced end members forming a supporting stand and having inwardly turned channels on the corners thereof having spaced orifices, two drawing boards adjustably supported on opposite sides of said stand, rolls having flanges rotatably secured on the upper end of said boards and being positioned in said channels, links pivotally supported at their upper ends to said boards a distance from said rollers and being pivotally secured to said end members at their other ends, whereby said boards may be moved to various angles, the axle of said rolls being slidably supported on said table, the outer end protruding through said rolls, springs on said axles adapted to yieldingly hold said rolls in said channels and said protruding ends in said orifices and means whereby said protruding ends may be disengaged by manually pressing said flanges toward said boards.

4. A device of the class described, comprising spaced channels having orifices and the flanges being turned inward, a drawing board, the upper end having supporting means being movably mounted in said channels, the other end of said board having supporting links whereby when said supports are moved in said channel, said board will be caused to assume different angles, said supports comprising rollers adapted to be embraced by said channel and having flanges, a bracket secured to said board and shafts slidably mounted in said brackets having springs adapted to move said shafts and rollers outwardly, the free ends acting as axles for said rollers and protruding therethrough and being adapted to be engaged by said orifices whereby said flanges may be manually pressed inwardly and thereby cause said projecting ends to disengage said orifices whereby said board may be moved and locked at selective angles.

5. A device of the class described having spaced end members and means therebetween forming a stand, drawing boards adjustably supported on opposite sides of said stand, said drawing board supports comprising guiding members on said end members, guide members secured to said boards near the upper corners thereof adapted to be slidably engaged by said guiding members, means whereby said guide members may be selectively locked to said guiding members, links pivotally secured at one end to said boards a distance from said guide members, the other ends being pivotally secured to said end members and positioned whereby said board may be moved to selected angles, two rolls of paper rotatably supported between said end members and positioned whereby the paper on each roll may be threaded over the adjacent board and secured thereto whereby said boards are free to move to various positions without detaching the paper from said rolls.

6. A drafting table of the class described, comprising end members having channels with spaced orifices therein and means for securing said end members in spaced relation forming a

stand, a drawing board adjustably supported on said end members, said adjustable supporting means comprising guide means near the upper corners of said board being slidably mounted in said channels, links pivotally secured at their outer ends to said board a distance from said guide means and being pivotally secured to said end members at their other ends, whereby said board may be moved to various angles, said guide means comprising rollers being operatively engaged by said channels and having bearing axles with protruding ends, said ends being adapted

to engage said orifices, flanges on said rollers being of a diameter to thereby project past the outer surfaces of said channels whereby said protruding ends may be manually disengaged by pressure on said flanges, paper holding means on said board and means on said stand in rear of said board adapted to retain a supply of endless paper being positioned whereby the paper may be threaded over said board and will remain intact while adjusting the board or when removing used portions of the paper. 5 10

MILLER B. COOK.
